UNITED STATES PATENT OFFICE.

BERTOLD BUXTBAUM, OF BERLIN-CHARLOTTENBURG, GERMANY.

ADJUSTABLE SETTING-UP PIECE FOR TOOLS AND WORK PIECES.

Application filed September 6, 1927, Serial No. 217,770, and in Germany February 15, 1927.

My invention relates to an adjustable setting-up piece intended for use especially in connection with tools and workpieces, but being, besides, applicable everywhere where it is necessary to adjust objects vertically.

More especially, the invention relates to an adjustable setting-up piece for lathe or turning tools and for similar tools. It is known that the cutting edge of said first-mentioned tools must be adjusted to a certain definite height relatively to the work-piece, and it is also often times necessary to adjust the tool to a certain definite angle with respect to the work-piece if the working of the work-piece is to be exact, and too quick wear and tear of the cutting edge of the tool to be prevented. The tool boxes with segmental adjustment as employed up to now for setting-up and adjusting the tools suffer from the drawback that in the case of an alteration of the vertical adjustment of the tool an alteration also of the cutting angle takes place, so that the cutting edge is quickly worn off on account of its wrong angular position. Also wedges which are shiftable with respect to one another are not suited as setting-up pieces for the tool, because the wedges require very much space in the tool holder and, besides, project forth from the front and the rear of the holder when they are shifted. Finally, when the wedges are shifted somewhat far away from one another the tool is supported only on a part of its length by the upper wedge.

Now, the object of the present invention is to obviate the drawbacks mentioned, and I attain this object by using as setting-up piece a chain-like member comprising a plurality of consecutively arranged parts movably connected with another the thickness of which decreases uniformly or in a steplike manner. When this chain-like member is used as setting-up piece for a tool there is preferably arranged between this piece and the tool a separate intermediate member, the upper and lower surfaces of which decrease also in thickness with respect to one another, the degree of the decrease being the same as that of the chain-like setting-up member proper, so that if this member and said piece are placed one upon the other, in opposite directions, the

uppermost surface lies horizontal, i. e. parallel to the surface of the base.

The invention is illustrated diagrammatically and by way of example on the accompanying drawing, on which Figure 1 is an end view and Figure 2 a side view of a tool carrier provided with a setting-up piece designed according to this invention; Figure 3 is a side view and Figure 4 a plan view of a part of the setting-up piece, the figures being drawn to an enlarged scale relatively to Figs. 1 and 2; Figure 5 is a view similar to Fig. 3 and shows a modification, Figure 6 is a transverse section therethrough; Figure 7 is a plan of another modification, Figure 8 a side view thereof, and Figure 9 is a modification of Fig. 8; Figures 10 and 11 are a longitudinal section through, and a plan of, another modification; Figure 12 is a longitudinal section through the separate intermediate member already mentioned in the preamble, and Figure 13 is an end-view of the same; Figure 14 is a representation similar to Fig. 2 and shows a constructional form in which said separate intermediate member and the tool are connected with each other, and Figure 15 is a transverse section through Fig. 14 in the plane I—I of the same and drawn to an enlarged scale; Figures 16—19 show some further modifications, all as fully described hereinafter. Fig. 20 is a further modification of the invention, in which the chain-like setting-up member is constructed in a step-like manner and Fig. 21 is a similar arrangement comprising two setting-up members made in accordance with Fig. 20.

On the drawing, *a* (Fig. 1) denotes the longitudinal tool guide and *b* the transverse tool slide which is located upon the former and can be shifted thereon by means of a threaded adjusting spindle *c*. *e* denotes the tool carrier proper which is held in place upon the slide *b* by means of a vertical bolt *d* and can be fixed by means of a nut *f* located on the top of said bolt. The holder *e* can be turned upon the bolt *d* and be fixed in any desired position. On the side counter to the said bolt the carrier proper *e* is provided with a horizontally projecting ledge *e*¹ through which extend two vertical clamping screws *h*. Below these screws is located upon the

- transverse slide b the chain-like setting-up piece i , the upper and lower surfaces of which are inclined relatively to one another under a certain angle, as shown in Fig. 2, the entire piece i representing a kind of wedge. k denotes the separate intermediate member which represents also a kind of wedge. In Fig. 2 the piece i and the member k are arranged one above the other and in opposite directions, as regards the inclination or obliquity, in consequence whereof the upper surface of the member k is horizontal. The tool m is supported directly by this member k and firmly pressed upon it by the screws h .
- 15 If the position of height of the tool is to be altered, without any alteration of its horizontal position, the screws h are loosened and the piece i is then so much shifted as required for the other position of the tool, that is to say, the piece i is shifted either to the left (Fig. 2) or to the right, according as whether the tool is to be lifted or lowered. The free ends of the piece i hang down, as shown, and do not hinder the workman in any way. If, 20 under circumstances an unusually long piece i is required, its free ends may be rolled up or done away with in a similar manner so that the place they need is the smallest possible.
- 25 The chain-like setting-up piece can be designed in various constructional forms, some of which are represented in Figs. 3-8. In Figs. 3 and 4 the links n of the setting-up piece are designed as hinge-halves; each of them is provided on one of its long sides with 30 a projection o^1 and in the other of its long sides with a recess o^2 receiving the projection of the respective neighbouring link or hinge-half, and the links or hinge-halves are movably connected with each other by pins p prevented, of course, from leaving their proper places.
- 35 In Figs. 5 and 6 the chain-forming parts n^1 are movably connected with each other by a strap q located in bottom recesses r of the parts n^1 and connected with these latter by rivets w . The lower edges of the parts n^1 are preferably bevelled in order to permit the free ends of the setting-up piece to hang down, as in Fig. 2. Above the band q the 40 abutting surfaces of the links n^1 are preferably also somewhat inclined with respect to one another in order to attain that fine chips entering, perhaps, into the joints do not prevent these latter from closing. The object of the recess r is to bring about that the pressure is transmitted directly by the links n upon the upper surface of the tool rest b , and the band q is not compressed by this pressure.
- 45 In Figs. 7 and 8 the chain-forming parts are formed by small rollers n^2 having axial bores through which pass pins p^1 connected with each other by links s and s^1 .
- 50 The constructional form of the chain-like setting-up piece shown in Fig. 9 corresponds

essentially to the constructional form shown in Fig. 8, there being only the difference that the rollers n^2 have flat top faces and flat bottom faces, as shown.

55 In Figs. 10 and 11 the setting-up piece consists of rectangular cells n^3 pressed, preferably, of sheet-metal and enclosing wedges u . Below these wedges are insertions v , the arrangement being preferably such that (for instance in the direction from the left to the right, Figs. 10 and 11) every following cell 60 contains one insertion more than the cell preceding it whereby the advantage is attained that all wedges can be of equal size. The wedges u , the insertions v , and the cells n^3 are 65 preferably connected with each other, for instance by rivets v^1 .

70 The separate intermediate member k shown in Figs. 12 and 13 is U-shaped in transverse section, that is to say, it forms an inverted U, 75 and the depth of the bottom groove decreases from the right to the left. The clear width of this groove between the lateral boundary ledges k^1 corresponds practically to the breadth of the chain-like setting-up piece so 80 that this latter is guided between said ledges, whereby lateral displacement of the setting-up piece is prevented.

85 The separate intermediate member k may be arranged loosely between the piece i and the tool or it may be connected with the same in any suitable manner. A suitable constructional form is shown in Figs. 14 and 15 in which plate springs z are affixed to the lateral faces of the intermediate pieces k by screws t , 90 for which latter other, equivalent, means may be employed. The upper faces of said springs contact with the lateral surfaces of the tool m and hold this securely in place so that the tool is shiftably connected with the intermediate piece k . The advantage thereby obtained consists therein that the workman need handle only two parts instead of three.

95 The Figs. 16-19 show several possibilities of arranging the chain-like setting-up piece i and the separate intermediate member k , the intention in all these cases being to give the tool an oblique position, either upwardly, as in Figs. 16 and 17, or downwardly, as in Figs. 18 and 19. In Figs. 17 and 19 the tool m is supported solely by the piece i , in Figs. 16 and 18, however, by this piece, as well as by the member k , in which cases the obliquity or degree of inclination is greater than in the other case, in that both parts (the chain-forming setting-up piece and the separate intermediate member) are inclined in the same direction.

100 In Fig. 20 the upper surfaces of the individual parts n^3 of the chain-like setting-up member i^1 are not inclined uniformly with respect to the lower surfaces, but the parts n^3 are constructed in a step-like manner in that the thickness of each following part is greater or vice versa smaller than the thickness of 105

the preceding part. In this case the intermediate member k^1 is also constructed in a step-like manner the height and the length of these steps being adapted to the steps of the 5 chain-like member.

In Fig. 21 two setting-up members i^1 , i^2 of the kind illustrated in Fig. 20 are arranged above another in opposite directions so that the intermediate member k can be dispensed 10 with.

The number of the steps of the chain-like members made in accordance with Figs. 20 and 21 can be equal to the number of the individual parts of the chain-like member as 15 shown in these figures. However, if desired, there may be provided a greater or smaller number of steps.

If the parts in question are arranged in the manner shown in Fig. 2, that is to say, in such 20 a manner that the tool is in a horizontal position it is, of course of no consequence whether the superposed parts i and k are arranged just as in Fig. 2 or if they are turned horizontally by 180° , the thinner end of the piece i being then on the right and that of the member k on the left. However the arrangement 25 to be preferred is that in which the shorter free end of the piece i is located next to the workpiece so that the free space on this side 30 is obstructed as little as possible.

With the constructional forms of the invention, as illustrated on the drawings, the chain-like setting-up piece is arranged below the wedge k , but also the reverse arrangement 35 is possible, that is to say, the wedge k may be arranged above the setting-up piece in which case the wedge is preferably provided with a shoulder either at only one end or at both ends, the shoulder or shoulders contacting 40 with the front or the rear side of the tool rest or with both sides, as the case may be.

I claim:

1. An adjustable setting-up piece for use in connection with tools, work-pieces and similar objects, comprising, in combination, a plurality of consecutively arranged setting-up piece parts, the thickness of which decreases from one end of the piece to the other end thereof, and means connecting said parts 45 movably with each other.

2. An adjustable setting-up piece for use in connection with tools, work-pieces and similar objects, comprising, in combination, a plurality of consecutively arranged setting-up piece parts, the thickness of which decreases uniformly from one end of the piece to the other end thereof, and means connecting said parts 55 movably with each other.

3. In combination: an adjustable setting-up piece for use in connection with tools, work-pieces and similar objects, and comprising a plurality of consecutively arranged setting-up piece parts, the thickness of which decreases from one end of the piece to the 60 other end thereof, and means connecting said

parts movably with each other, and a separate intermediate member, the thickness of which increases from one end to the other end, the degree of the decrease of said piece and said member being equal, substantially 70 and for the purpose set forth.

4. An adjustable setting-up piece for use in connection with tools, work-pieces and similar objects, comprising, in combination, a plurality of consecutively arranged setting-up piece parts, the thickness of which decreases from one end of the piece to the other end thereof and which form open cells; wedge-shaped members located in these cells, and means for connecting said cells movably 75 with each other.

5. An adjustable setting-up piece for use in connection with tools, work-pieces and similar objects, comprising, in combination, a plurality of consecutively arranged setting-up piece parts, the thickness of which decreases from one end of the piece to the other end thereof and which form open sheet-metal-cells; wedge-shaped members located 80 in these cells, and means for connecting said cells movably with each other.

6. An adjustable setting-up piece for use in connection with tools, work-pieces and similar objects, comprising, in combination, a plurality of consecutively arranged setting-up piece parts, the thickness of which decreases from one end of the piece to the other end thereof and which form open cells; wedge-shaped members of equal size located 85 in these cells, insertions located in said cells below said wedge-shaped members and means for connecting said cells movably with each other.

7. An adjustable setting-up piece for use in connection with tools, work-pieces and similar objects, comprising, in combination, a plurality of consecutively arranged setting-up piece parts, the thickness of which decreases from one end of the piece to the other end thereof and which form open cells; wedge-shaped members of equal size located 90 in these cells, insertions located in different numbers in said cells below said wedge-shaped members and means for connecting said cells movably with each other.

8. In combination: an adjustable setting-up piece for use in connection with tools, work-pieces and similar objects, and comprising a plurality of consecutively arranged setting-up piece parts, the thickness of which decreases from one end of the piece to the other end thereof, and means connecting said parts 100 movably with each other, a separate intermediate member, the thickness of which increases from one end to the other end, the degree of the decrease of said piece and said member being equal and means connecting the intermediate member with the tool substantially as set forth.

9. In combination: an adjustable setting- 105

up piece for use in connection with tools, work-pieces and similar objects, and comprising a plurality of consecutively arranged setting-up piece parts, the thickness of which decreases from one end of the piece to the other end thereof, and means connecting said parts movably with each other, a separate intermediate member, the thickness of which

increases from one end to the other end, the degree of the decrease of said piece and said member being equal and plate springs connecting the intermediate member with the tool substantially as set forth.

In testimony whereof I have affixed my signature.

DR. BERTOLD BUXBAUM.
